UNITED STATES PATENT OFFICE.

RICHARD LONG, OF IOWA CITY, IOWA.

ROAD-GRADING MACHINE.

SPECIFICATION forming part of Letters Patent No. 352,198, dated November 9, 1886.

Application filed March 8, 1886. Serial No. 194,462. (No model.)

To all whom it may concern:

Be it known that I, RICHARD LONG, a citizen of the United States of America, and a resident of Iowa City, in the county of Johnson and State of Iowa, have invented a Road-Grading Machine, of which the following is a specification.

My object is to plow up ground at the sides of a road and carry and distribute the loose soil toward the center by means of machinery as rapidly as the machine is advanced, to round up the center of the road, and to save much of the time, labor, and expense incident to plowing, shoveling, and scraping ground in making roads.

My invention consists in the construction and combination of a carriage, a steering device, a plow-adjusting mechanism, a rotating carrier and distributor, a self-adjusting frame to support the rotating carrier and distributor, and an adjustable scraper, as herein-after set forth, pointed out in my claims, and illustrated in the accompanying drawings, in which—

Figure 1 is a top view, and Fig. 2 a side view, of the complete machine, and Fig. 3 a transverse section of the rotating carrier and distributor suspended from the carriage-frame by means of the self-adjusting frame and rollers.

A represents a wooden beam that may vary in size as desired.

A² is a cross-piece fitted to the center of the beam A, and rigidly fixed thereto by means of bolts and braces, or in any suitable way to produce a rigid carriage-frame of T shape.

B B are wheel-bearers, preferably made complete in one piece, of cast-iron, swiveled to the ends of the beam A by means of bearings formed in or fixed thereto.

B² are traction-wheels secured in the lower bifurcated ends of the bearers by means of axles in a common way.

C is a reach hinged to the end of the cross-piece A², to extend forward at right angles therefrom and parallel with the front end of the beam A.

C² is a right-angled frame suspended from and hinged to the end of the cross-piece A², by means of a metal bearer, C³, as clearly shown in Fig. 3.

D is a brace extending from the front end of

the beam A to the front end of the frame C². D² is a brace extending from the front end of the same frame to the central portion of the cross-piece A². These braces aid in retaining the front portion of the frame C² parallel with the reach C, so that the front end of the frame and front end of the reach will jointly serve as bounds in connecting the pole to the complete carriage.

F is a pole, having a cross-piece, F², at its rear end, hinged to the front ends of the parallel parts C and C² in such a manner that the cross-piece F² will project horizontally outward and at right angles from the front end of the reach C, to support a caster-wheel, G, as clearly shown in Figs. 1 and 2.

B³ are sprocket-wheels formed on or fixed to the wheel-bearers B, to extend horizontally under the beam A.

H is a rotating shaft in bearings fixed to the cross-piece A². It has a pinion, H², fixed to its inner end, and a crank, H³, at its outer end.

J is a metal bearing fixed to the side and center of the beam A, to retain a sliding rack, J², that rests upon the pinion H². Chains J³, fixed to the opposite ends of the rack, are passed around the sprocket-wheels in opposite directions, and connected by means of a rod 80 that is passed diagonally through a bore in the cross-piece A², under the beam A, as indicated by dotted lines in Fig. 1, in such a manner that when the shaft H is rotated the pinion will move the rack J² longitudinally to pull the chains in opposite directions, so that the chains will, by means of the sprocket-wheels, turn the wheel-bearers B and traction-wheels B² in opposite directions, as required, to deflect the complete machine to the right or left from a straight line of advance.

K is the beam of a plow pivoted in a metal bearer, K², that is fixed to the end of the cross-piece A².

K³ is a brace fixed to the front end of the plow-beam, and pivoted to the rear end and corner of the frame C² in such a manner that the front end of the plow-beam can be raised and lowered.

L is a shaft in a bearing formed in or fixed to the reach C. It has a gear-wheel, L², fixed to the outer end and a lever-handle, L³, to the inner end.

M is a rack pivoted to the plow-beam K at

its lower end, to extend vertically and engage the gear-wheel L^2 in such a manner that when the shaft L is rocked the rack will be moved longitudinally by means of the gear-wheel L^2 , 5 as required, to raise or lower the front end of the plow-beam for the purpose of governing the depth of the plow. The front end of the plow-beam is flexibly connected with the cross-piece F^2 by means of a staple and link.

10 N is the rim of my rotating carrier and distributor, preferably made in sections of plate-steel riveted together. It has an annular flange, N^2 , extending outward from its lower edge, and a corresponding flange, N^3 , extending inward from its top edge.

15 P is a circular platform, preferably made of sheet-steel, fitted upon the flange N^2 , and fixed thereto by riveting, or in any suitable way.

P^2 is a hub rigidly connected with the rim 20 N by means of radial spokes P^3 , cast integral with the hub and rim, or in any suitable way.

25 R is a metal plate fixed against the bottom of the hinged frame C^2 , to serve as a bearing for the axle R^2 , that is extended up through the frame and down through the hub to suspend the hub and complete the rotating carrier.

R^2 is a roller-bearer on the end of the plate 30 R . Perforated ears S extend in opposite directions from the plate R .

35 S^2 is a brace provided with a pin at its rear end, which pin enters the front perforated ear. The front end of the brace is fixed to the front portion of the frame C^2 .

No. 1 is a roller placed loosely on a journal 40 fixed to the corner of the frame C^2 in such a manner that it will be continually in contact with the top surface of the flange N^3 of the rim N . No. 2 is a corresponding roller on the bearer R^3 , to engage the under side of the same flange. The two rollers thus combined with the rotating carrier keep it in balance on its inclined axle, to prevent friction and facilitate its rotary motion.

45 T is a scraper composed of a flat metal plate fixed to the end of a frame, T^2 , to project down upon the top surface of the platform P of the rotating carrier, to push off loose soil as the carrier revolves.

50 T^2 is an arm extending from the frame T^2 , pivoted to the perforated ear S , extending rearward from the end of the plate R in such a manner that the scraper can be adjusted relative to the frame C^2 and the carrier, as required, to regulate the pushing off of the loose 55 soil from the platform of the carrier at different distances from the plow.

60 The pivoted arm T^2 , carrying the scraper, is secured to the perforated ear S by means of a screw-threaded bolt and nut in such a manner that the nut can be drawn tight to rigidly clamp the arm fast in any position or angle it may be set relative to the line of advance.

65 X represents a driver's seat fixed to the carriage-frame.

65 In the practical use of my invention I hitch horses to it by means of the tongue and a double-tree, and then advance it along the side of

a road to plow ground loose in a common way. As the plow is advanced the loose ground is thrown from the mold-board of the plow direct 70 upon the circular platform of the inclined rotating carrier, and the outer edge of the platform rests and moves upon the surface of the road in a line parallel with the furrow made by the plow, and close to the plow, in such a 75 manner that it will be actuated by the friction upon the ground to rotate upon its axis and carry the soil away from the plow to let it drop off between the plow and the scraper, as required, to distribute it over the surface of the 80 road. By thus advancing the machine successively at the opposite sides of the road and in opposite directions the ground at the sides will be loosened and carried and distributed to the center of the road by the operation of 85 the machine, and the road graded.

I claim as my invention—

1. The carriage-frame composed of the beam A , cross-piece A^2 , the pivoted bearers B , carrying-wheels B^2 , the hinged frame C^2 , braces D D^2 , the reach C , tongue F F^2 , the caster-wheel G , and steering mechanism, for the purposes specified.

2. The shaft H , having a pinion on its inner end and a crank-handle at its opposite end, a 95 sliding rack, J^2 , ropes or chains J^3 , and the sprocket-wheels B^3 , arranged and combined with a tractable carriage, and adapted to direct the same, substantially as shown and described, for the purposes stated.

3. A tractable carriage composed of a straight beam having traction-wheels under its ends, a cross-piece extending laterally from the central part of the straight beam and having a plow suspended from its free end, a right-angled frame hinged to the opposite end of the cross-piece and carrying a rotating ground-carrier in an inclined position at the side of the suspended plow, a reach hinged to the free end of the cross-piece to extend forward 105 over the suspended plow-beam, a tongue having a cross-piece journaled to the front end of the reach and pivoted to the front end of the right-angled frame and supported upon a caster-wheel, arranged and combined to operate in the manner set forth, for the purposes stated.

4. The carrier composed of the rim N , having flanges N^2 and N^3 , the circular platform P , the hub P^2 , and spokes P^3 , supported upon rollers Nos. 1 and 2, for the purposes stated.

5. A rotating carrier having a circular platform extending outward from its bottom edge, and an annular flange extending inward from its top edge, in combination with an inclined 125 frame hinged to a tractable carriage, and rollers carried by the incline frame to engage the annular flange at the opposite sides of the rim, one on the top surface and the other the bottom, to operate in the manner set forth, for the 130 purposes stated.

6. The hinged frame C^2 , the plate R , the roller-bearer R^3 , the axle R^2 , the rollers Nos. 1 and 2, and the rotating carrier composed of

the rim N, having flanges N² and N³, a circular platform, P, a hub, P², and spokes P³, constructed, arranged, and combined to operate in the manner set forth.

5 7. A road-grading machine composed of the following elements, to wit: a rigid T-shaped or three-armed frame having traction-wheels swiveled to two of its corners, an auxiliary right-angled frame hinged to the center of the main frame, a reach hinged to the free end and lateral extension of the main frame, a pole or tongue journaled or pivoted to the front end of the reach and the front end of the auxiliary hinged frame, a caster-wheel under the front 10 end of the reach and rear portion of the tongue, a

plow suspended under the free end of the lateral extension of the main frame, mechanism for raising and lowering the plow, a rotating carrier suspended from the auxiliary hinged frame in an inclined position to allow its outer edge 20 to engage the ground near the plow, a scraper to engage the top surface of the circular platform of the rotating carrier, and mechanism for steering the machine, to operate in the manner set forth.
